Patented June 17, 1969

214,453

STUDENT LABORATORY DESK

Theodore G. Anker, West Englewood, N.J., assignor to
S. Blickman Inc., Weehawken, New Jersey

Continuation-in-part of design application Ser. No. 4,334,
Oct. 19, 1966. This application June 3, 1968, Ser. No.
12,177

Term of patent 14 years

Int. Cl. D6—01

U.S. Cl. D33—7

Fig. 1.

Fig. 2.

FIGURE 1 is a perspective view of a student laboratory desk, looking at a corner and side thereof; and

FIGURE 2 is another perspective view of the student laboratory desk shown in FIGURE 1, looking at an opposite corner and side thereof.

This application is a continuation-in-part of my earlier filed application Ser. No. D4,334, filed Oct. 19, 1966 and now abandoned.

I claim:

The ornamental design for a student laboratory desk, substantially as shown.
